UNITED STATES PATENT OFFICE.

GEORGE G. POWERS, OF CHICAGO, ILLINOIS, ASSIGNOR TO UNION WIRE MATTRESS COMPANY, OF CHICAGO, ILLINOIS, A CORPORATION OF ILLINOIS.

BED-SPRING.

1,243,099.

Specification of Letters Patent. Patented Oct. 16, 1917.

Application filed November 29, 1915. Serial No. 63,942.

To all whom it may concern:

Be it known that I, GEORGE G. POWERS, a citizen of the United States, residing at Chicago, in the county of Cook and State of Illinois, have invented certain new and useful Improvements in Bed-Springs, of which the following is a specification.

My invention pertains to features of novelty and advantage in bed-springs or wire-mattresses, and the like, and concerns more particularly the manner of supporting the spring or mattress on the bedstead frame or side-rails.

One object of the invention is to so construct and mount the bed-spring as to balance or oppose the strains imposed upon the same as much as possible, to permit the structure to be made of light gage material without loss of strength, and also to improve the functional characteristics of the appliance.

A further purpose of the invention is to produce a structure of this character, wherein the bed-spring will tend to maintain its horizontal disposition even though unevenly loaded, as by occupants of greatly differing weights.

In my prior patent, No. 1,154,936, bed spring, granted September 28, 1915, there is shown a construction of this general character, wherein the mattress-frame and the fabric mounted thereon are supported from a hanger-construction resting on the bed-frame by means of coil tension springs, the fabric and these springs both being located above the side-rails of the mattress-frame, the hanger-construction being positioned between the fabric and such side-rails. In the structure of the patent, it will be noted that all of the strain imposed on the mattress-frame side-bars is at one side, that is, above the side-bars, which requires substantial end supports or brackets and results in an unnecessary cumulative effect of the strain produced in the structure.

As has been indicated above, one of the objects of the present invention is to so modify the device of the patent as to, at least in part, neutralize or oppose such strains, for the purpose indicated.

In the preferred embodiment of the invention this is brought about by having the fabric above the mattress-frame side-bars and the hanger-construction and the supporting springs below such side-bars, so that

there will be a more even or balanced distribution of the strains produced, which permits the employment of a lighter weight structure without sacrifice of strength.

In order that those skilled in this art may have a full understanding of the invention, I have illustrated several embodiments of the same in the accompanying drawings which form a part of this specification and to which reference should be made in connection with the following detailed description. In the various views of these drawings like reference characters refer to the same parts.

In these drawings:

Figure 1 is a longitudinal section through the bedstead and wire-mattress;

Fig. 2 is a fragmentary plan view of the structure shown in Fig. 1;

Fig. 3 illustrates in longitudinal section the connection between the mattress-frame and the hanger-construction;

Fig. 4 shows the same parts in cross-section;

Fig. 5 is a fragmentary plan detail view of the spring attachment between the mattress-frame and the hanger-construction;

Fig. 6 illustrates the connection of the flexible wire or strap supports for the spiral springs beneath the central portion of the fabric;

Fig. 7 is a view similar to Fig. 1 of a modified construction;

Fig. 8 is a fragmentary plan view of the parts shown in Fig. 7;

Fig. 9 is a detail cross-section on an enlarged scale on line 9—9 of Fig. 8;

Fig. 10 is a fragmentary plan view of another modification; and

Fig. 11 is an enlarged cross-section on line 11—11 of Fig. 10.

Referring to the form of device shown in Figs. 1 to 6 inclusive, it will be noticed that a portion of the bedstead-frame is illustrated, i. e., two corner-posts 20 and 21 connected together by the usual side-rail 22.

Inasmuch as both sides of the mattress-construction are alike, it is only necessary to illustrate and describe one side portion of the same. The mattress-frame comprises two side-bars or rods 23, each of which at each end is equipped with a standard or bracket 24, composed of a metal strap bent to provide a part 25 extended both above and below the side-bar, as shown, and equipped

with a socket 26 receiving the end of such side-bar. At its top this member 24 is bent down as indicated, to provide an ear 27 on top of the side-bar, the bottom-end of member 24 being bent inwardly at 28, such portion having riveted thereto a supplemental bracket 29 projecting under the bar 23, the two parts 27 and 29 being secured to the side-bar by means of rivets 30. The parts 27 and 29 where they contact with the top and bottom faces respectively of the side-bar are curved, as shown in Fig. 4, to secure an effective contact between the elements. Each end of the mattress-frame at its top 15 is equipped with a transverse angle-bar 31, to which a wire-fabric 32 of any suitable construction is connected by means of the usual helical springs 33.

As is customary in structures of this general character, the side-margins of the mattress are provided with flat metal straps or ribbons 34 connected at their ends by means of helical springs 35 with the cross-bars 31, these parts 34, being associated with 25 the adjacent portions of the wire-fabric by suitable links or other connecting elements.

Near each end of the bedstead a cross-bar 36 is employed, the major portion of each of such bars being in a vertical plane, as 30 shown in Fig. 2, the end sections being bent horizontally at 37 and then upwardly and outwardly at 38 (Fig. 4), such latter parts resting upon the adjacent bedstead side-rails.

35 Beneath the central portion of the fabric 32 a supplemental cushion is employed comprising a plurality of upright, tapered, spiral-springs 39, 39, interlocked at their upper ends with one another and with a 40 border wire or rod 40 by means of connecting or locking wires 41 of any suitable shape or form. The lower ends of these springs are mounted on cross-bars 42, 42, the major portion of each of which is in a vertical plane, the ends of such bars being bent 45 horizontally and then bent down into hook form, as shown in Fig. 6. These bars 42 are supported by means of two wires or flexible straps 43, 43, one at each side of the mattress, which engage under the hooked ends of bars 42, as illustrated in Fig. 6. As 50 is shown more clearly in Figs. 3 and 5, each end of each of these flexible wires or straps 43 is bent into hook form at 44 which extends through an aperture of a plate 45 or 45^a located directly above and resting upon the horizontal part 37 of the corresponding cross-bar 36, as is indicated in Fig. 4. By means of a pair of tension springs 46, 46, 55 each plate 45 and 45^a is elastically or yieldingly connected to the corresponding ear 28 of the adjacent bracket or support 24. By means of rivets 47 a tongue 48 is secured to and below each plate 45 so that the cross-bar 36 is slidingly received between the two 60

parts 45 and 48, as is clearly shown in Fig. 3. Plates 45^a are riveted or bolted directly to the mating cross-bar.

From this description of the construction of this appliance, it will be apparent that 70 the weight of the mattress-frame, its fabric, and the load imposed on the latter, is borne by the springs 46, which act as the sole supporting means for these parts. It should be observed, however, that owing to the yielding capabilities of the fabric 32 or its attachment springs 33, a part of the load resting upon the fabric will be transmitted through the springs 39 to the yielding or flexible wires or straps 40, and such portion 80 of the load will tend to strain or expand the springs 46 inwardly. The remainder of the load is transmitted through the frame to the outer ends of the springs 46 and will tend to expand the springs outwardly and 85 downwardly. Owing to this opposed action on these supporting springs, the mattress as a whole tends to preserve its horizontal relation even though unevenly loaded.

Inasmuch as the springs 33 and the 90 weights of the occupants on the fabric act on the brackets 24 above the level of the side-bars 23 of the mattress-frame and the springs 46 act upon the same supports below such side-bars, these strains or stresses are 95 opposed the one to the other, which permits the employment of lighter weight parts in the construction and a more balanced or proper distribution of the strains.

In Figs. 7, 8, and 9, a somewhat modified 100 construction is illustrated.

In this instance, the cross-bars 36 are riveted to or otherwise associated with the plates 45 and 45^a, and there is no yielding cushion interposed between the fabric and 105 the supporting bars 42, but instead, a suitable number of cushion springs 49 are inserted between the mattress-frame side-rails 23 and such cross-bars. This may be conveniently accomplished by riveting or otherwise securing spring-caps 50 to the under sides of the mattress-frame side-rails and providing the ends of the bars 42 with any suitable spring-holding-means, such as bosses 51. In this instance the ends of the 110 bars 42 have hook-portions 52 pressed out thereof and adapted to receive the flexible or yielding wires or straps 43.

By employing these cushion-supporting springs 49, a portion of the weight imposed 115 on the mattress is transmitted to the wires or flexible straps 43 through the mattress-frame side-rails instead of through an intermediate cushion beneath the central portion of the fabric proper.

In the still further modification of Figs. 10 and 11 the features of both of these styles of construction are employed, and require no further explanation.

Those skilled in the art will have no diffi- 130

culty in appreciating the construction and functional advantages accruing from the employment of a structure embodying my invention and they will also understand that 5 the principle of construction is capable of use in structures considerably different in details from those herein presented. That is to say, many minor mechanical changes may be made in the appliances illustrated 10 and described without departure from the essence of the invention and without the sacrifice of any of its substantial benefits.

I claim:

1. In a structure of the character described, the combination of a mattress-frame having longitudinal side-bars, a fabric supported on said frame above the level of said side-bars, cross-bars adapted to rest on the bedframe, flexible straps connecting said 20 cross-bars, and elastic means connecting said mattress-frame at points below the level of said side-bars to said flexible straps, whereby said mattress-frame and fabric are supported by said elastic means, substantially as described.

2. In a structure of the character described, the combination of a mattress-frame having longitudinal side-bars, a fabric supported on said frame above the 30 level of said side-bars, cross-bars adapted to rest on the bed-frame, flexible straps connecting said cross-bars, elastic means connecting said mattress-frame at points below the level of said side-bars to said straps, and supporting means interposed between said side-bars and straps, substantially as described.

3. In a structure of the character described, the combination of a mattress-frame having longitudinal side bars, a fabric supported on said frame above the 40 level of said side-bars, cross-bars adapted to rest on the bed-frame, flexible-straps connecting said crossbars, elastic means connecting said mattress-frame at points below the level of said side-bars to said straps, and yielding means interposed between said side-bars and straps, substantially as described.

4. In a structure of the character described, the combination of a mattress-frame having longitudinal side-bars, a fabric supported on said frame above the 50 level of said side-bars, cross-bars adapted to rest on the bed-frame, flexible straps connecting said cross-bars, supporting elastic means connecting said mattress-frame at points below the level of said side-bars to said straps, supporting means interposed between said fabric and straps, and sup- 60 porting means interposed between said side-bars and straps, substantially as described.

5. In a structure of the character described, the combination of a mattress-

frame having longitudinal side-bars, a yielding fabric supported on said frame 65 above the level of said side-bars, cross-bars adapted to rest on the bed-frame, flexible straps connecting said cross-bars, a support mounted on said flexible straps, supporting elastic means connecting said mattress-frame at points below the level of said side-bars to said straps, yielding means interposed between said fabric and said support, and yielding means interposed between said side-bars and said support, substantially as described.

6. In a structure of the character described, the combination of a mattress-frame having longitudinal side-bars, a yielding fabric supported on said frame above the 80 level of said side-bars, a yielding hanger-construction adapted to rest on the bed-frame, springs supporting said mattress-frame from said hanger-construction and connected to the mattress-frame below the 85 level of said side-bars, yielding means interposed between said fabric and hanger-construction, and yielding means interposed between said mattress-frame and hanger-construction, substantially as described.

7. In a structure of the character described, the combination of a mattress-frame having longitudinal side-bars, a yielding fabric supported on said frame above the 90 level of said side-bars, a yielding hanger-construction adapted to rest on the bed-frame, elastic means supporting said mattress-frame from said hanger-construction and connected to said mattress-frame below the 95 level of said side-bars, and yielding means interposed between said fabric and hanger-construction, substantially as described.

8. In a structure of the character described, the combination of a mattress-frame 100 having longitudinal side-bars, a fabric supported on said frame above the level of said side-bars, a yielding hanger-construction adapted to rest on the bed-frame, elastic means supporting said mattress-frame from 105 said hanger-construction and connected to said mattress-frame below the level of said side-bars, and supporting means interposed between said mattress-frame and hanger-construction, substantially as described.

9. In a structure of the character described, the combination of a mattress-frame having longitudinal side-bars, a fabric supported on said frame, a yielding hanger-construction adapted to rest on the bed-frame, elastic means supporting said mattress-frame from said hanger-construction, and supporting means interposed between said mattress-frame and hanger-construction, substantially as described.

125
GEORGE G. POWERS.
